ELECTRICAL CONNECTION MEANS

Harry A. Douglas, Bronson, Mich., assignor to
 Kingston Products Corporation, a corporation
 of Indiana

Application August 23, 1935, Serial No. 37,492

2 Claims. (Cl. 173—328)

My invention relates to electrical connection means, and more particularly to means for receiving conductor terminals of the snap type, and the principal object of my invention is to provide new and improved electrical connection means of these types.

In the drawing accompanying this specification and forming a part of this application, I have shown, for purposes of illustration, one form which my invention may assume, and in this drawing:

Figure 1 is a perspective view illustrating the embodiment of my invention.

Figure 2 is a perspective view of the embodiment shown in Figure 1, the embodiment having been turned 180° to show the rear side thereof, and

Figure 3 is an enlarged longitudinal section of the embodiment, including, in addition, a plug conductor terminal adapted to cooperate therewith.

Referring to the drawing, the embodiment herein disclosed comprises a terminal post 10, mounted on a base 11, the base being fragmentarily shown. The terminal post 10 comprises a body portion 12, here shown to be formed of a single piece of channel stock bent into a generally right angular formation. The body portion 12 includes a generally vertical wall 13 having extending channel walls 14, and a generally horizontal wall 15 having extending channel walls 16 integrally joining the channel walls 14, the horizontal wall 15 serving as a foot for the body portion 12, and being integral with the vertical wall 13 and extending at right angles therefrom at the lower end thereof.

The vertical wall 13 is provided with a plug terminal receiving recess, here shown to be a circular aperture 17 adjacent the top margin thereof. Partially circumscribing the aperture 17 is a laterally extending flange 18 having its inner surface continuous with the aperture 17. The flange 18 may be formed by drawing out the metal theretofore forming part of the vertical wall 13 which had been removed to form the aperture 17. As shown in Figures 1 and 2, the flange 18 merges with integral outwardly extending shoulders 19, which in turn integrally join the channel walls 14 of the vertical wall 13. The shoulders 19, at their inner surfaces, form abutments 20, for a purpose hereinafter to be described.

The horizontal wall or foot 15 is provided with an aperture 21, through which a screw 22 or any other suitable fastening means may be disposed,

to fasten the body portion 12 to the base 11. The foot 15 may be prevented from turning about the fastening means 22 by a projection 23 struck downwardly from the foot 15, the projection 23 being adapted to be disposed in a recess 24 formed in the upper surface of the base 11.

Biassing means are provided for cooperation with the body portion 12, and comprise a spring member 25, here shown to be formed of spring wire, and generally S-shaped, providing free legs 10 26 and 27. The legs 26 and 27 of the spring member 25, and the portion thereof connecting the legs 26, 27 are movable relative to each other, approximately in a general plane of relative movement.

To assemble the biassing means with the body portion 12, the spring member 25 is positioned so that the leg 26 thereof is in abutting engagement with the inner surfaces 20 of the shoulders 19, and the leg 27 is in abutting engagement with the upper surface of the horizontal wall 15, the spring member 25, it will be appreciated, being of a suitable width to operatively fit within the channels 14 and 16 of the walls 13 and 15 respectively. With the spring member in this position, a portion of each channel wall 14, intermediate the shoulders 19 and the channel walls 16 is bent inwardly, as shown at 28, to provide suitable guiding means for operatively positioning the spring member 25. As best shown in Figure 1, the leg 26 forms a chord across the aperture 17 formed in the vertical wall 13. The terminal post 10 is assembled as a unit, in the manner hereinbefore described, and the fastening means 22 may be disposed through the aperture 21 in the horizontal wall 15, and the screw threaded end thereof engaged in a suitable screw threaded aperture formed in the base 11.

In Figure 3 is shown a plug conductor terminal 29, adapted to cooperate with the terminal post 10, and comprising a generally cylindrical portion 30 having an annular furrow 31 formed therein, the plug conductor terminal 29 being provided with a frusto-conical end 32. A conductor 33, disposed within the plug conductor terminal 29, 45 may be fastened thereto, as by swaging, indicated by the swedge indentations 34.

The plug conductor terminal may be moved to operative position with respect to the terminal post 10 by inserting the frusto-conical end 32 50 into the aperture 17, initial insertion causing the frusto-conical end to cam the leg 26 of the spring member 25 downwardly, to provide for the accommodation of the cylindrical portion 30, and further movement causing the leg 26 of the spring 55

member 25 to snap into the annular furrow 31, thus yieldably holding the plug conductor terminal in operative position. Withdrawal movement on the plug conductor terminal 29 causes the 5 tapering surface of the annular furrow 31 to cam the leg 26 downwardly, permitting removal of the plug conductor terminal from operative position.

From the foregoing it will be apparent to those skilled in the art that the illustrated embodiment 10 of my invention provides a new and improved electrical contact and connection means, economical in construction and assembly, and accordingly, accomplishes at least the principal object of my invention. It further will be obvious to those 15 skilled in the art that the illustrated embodiment of my invention may be variously changed and modified without departing from the spirit of my invention, or sacrificing all of the advantages thereof, and that accordingly, the disclosure herein 20 in is illustrative only, and my invention is not limited thereto.

I claim:

1. Receptacle means, comprising: a wall, having 25 an aperture for receiving a conductor terminal, and having also angular flanges extending from opposite marginal surfaces, said flanges being bent toward each other to form shoulders; and biasing means, comprising a resilient wire bent to provide a plurality of overlying and connected portions, said biasing means being positioned in juxtaposed relation with a lateral sur-

face of said wall, and said portions being movable relative to each other in a plane generally parallel to the plane including said lateral surface, one end portion bearing against a part of said wall, and the opposite end portion being urged toward abutment with said shoulders, and being in position to yieldably engage a conductor terminal disposed in said wall aperture.

2. Receptacle means, comprising: a body, formed of sheet-metal channel stock bent to 10 form a base and a portion extending angularly from said base, the web of said portion being provided with an aperture for receiving a conductor terminal, and the side flanges of said portion having inwardly turned projections extending generally parallel to said web but being spaced from said web, and certain portions of said side flanges being bent inwardly toward each other to form shoulders and then further bent to 15 form a surface wall margining said aperture; and biasing means, comprising overlying and connected portions confined to movement within the space defined by said projections and the adjacent surface of said web, said portions being movable relative to each other, and having one end portion bearing against the web of said base, and the opposite end portion biased toward abutment 20 with said shoulders, and being in position to yieldably engage a conductor terminal disposed in said web aperture.

HARRY A. DOUGLAS.
